UNITED STATES PATENT OFFICE.

LEGRAND B. HARMON, OF CARYSVILLE, AND JASPER N. NUTT, OF SIDNEY,
OHIO.

FENCE-POST.

SPECIFICATION forming part of Letters Patent No. 380,627, dated April 3, 1888.

Application filed January 30, 1888. Serial No. 262,420. (No model.)

To all whom it may concern:

Be it known that we, LEGRAND B. HARMON, of Carysville, Champaign county, Ohio, and JASPER N. NUTT, of Sidney, Shelby county, 5 Ohio, citizens of the United States of America, have invented certain new and useful Improvements in Fence-Posts, of which the following is a specification, reference being had therein to the accompanying drawings.

10 Our invention relates to fence-posts for wire fences; and it consists in certain details of construction, which will first be described in connection with the accompanying drawings, and then pointed out in the claims.

15 Figure 1 of the drawings is a perspective view of our post with two anchors attached. Fig. 2 is a perspective view of an anchor and a portion of the post. Fig. 3 is a rear elevation of a portion of the post with an anchor 20 attached. Fig. 4 is a side view of a portion of the post, illustrating the wire-receiving kerfs.

Referring to the drawings, A represents the post, stamped up from metal, and for the purpose of description it may be said to be V-shaped in cross-section. The front edge of the post, however—that is to say, the edge to which the sides *a a* converge—is rolled up into a nearly half-round bead, *b*, the function of which bead, aside from giving strength to the post, 30 will be presently explained.

For the purpose of attaching the fence-wires *w* to the post, we cut kerfs *c* in its front edge, which kerfs incline downward and rearward, as at 1, then forward, as at 2, and finally terminate in perforations, as at 3, Fig. 4, in which latter the wires are to be inserted. It will be noticed that these wire-receiving perforations 35 are located at the rear of bead *b*, and that consequently the lip *l*, formed by the kerf, will, 40 owing to the comparative rigidity of the bead, be caused to spring back with considerable force after the wire has been passed down through the kerf and forward into the perforation, whereby the wire will be securely held 45 without the interposition of wedges or other like devices, it being understood that the diameter of the perforation is somewhat less than that of the wire; and it will also be noticed that by reason of the bead we are enabled to

make this very desirable form of kerf without 50 cutting so deep into the post as to materially weaken it.

For the purpose of maintaining the post in an erect position when in the ground, we employ one or more anchors, B, removably secured to the front edge of the post. This anchor we prefer to make in the form shown in the drawings—that is to say, by bending the respective ends of a rectangular piece of metal in opposite directions. An anchor of this form, 55 when attached to the post, offers greatly-increased resistance to deflection of the post in any and all directions, as will be readily apparent on inspection of Fig. 1 of the drawings.

In order to attach the anchor to the front 60 edge of the post, and at the same time to give it a broad bearing, so that it cannot swing out of position, we cut two transverse slits through the bead on the post and a short distance into the sides *a a*, and then sever the intermediate 65 portion by a vertical cut down the center of the bead, after which we bend back each severed portion into a position at right angles to the axis of the post, thus forming bearings or anchor-braces 4 and leaving an opening, 5, for 70 the reception of the tongue on the anchor. This tongue *t* is formed by cutting two parallel slits, 6, in the anchor and bending the intermediate portion rearward into concave 75 form, as viewed from the front, and the other 80 portions on each side of the tongue into convex form, so that while the tongue passes rearwardly through the opening 5 in the post the convex parts will fit neatly around the bead. A wedge, *d*, or other suitable device is then 85 inserted between the tongue and the rear side of the bead, as seen in Fig. 3, which serves to key the anchor to the post.

One anchor will generally be found sufficient to secure the post; but two or more may be 90 used if the nature of the soil demands them.

By the above description our invention is clearly distinguished from the V-shaped post having oblique kerfs cut across its front edge, which kerfs terminate directly in apertures for 95 the reception of the wire, for by that construction there is little or no resiliency in the lip, and therefore, in order to hold the wire firmly,

it has been found necessary to either wrap it around posts at intervals or to secure it to each post by means of wedges and like devices.

We are aware that an anchor made from a rectangular piece of metal with its ends bent in opposite directions from each other is not new; but we believe we are the first to combine this desirable form of anchor with a beaded V-shaped post.

10 Having thus described our invention, what we claim as new, and desire to secure by Letters Patent, is—

15 1. A metallic V-shaped fence-post with an approximately semi-cylindrical bead on the edge formed by the meeting of the sides, having a series of wire-securing lips on said edge, the said lips being formed by downwardly and rearwardly inclined and forwardly-extending kerfs terminating in perforations in rear of the 20 bead, substantially as described.

2. The combination, with a V-shaped metallic fence-post having an approximately semi-cylindrical bead on the edge formed by the meeting of the sides, an opening through said 25 beaded edge, and an anchor-brace integral with the post on each side of said opening, of an anchor having a rearwardly-extending

tongue to pass through the opening in the post and a key or other suitable device to pass between the tongue and the rear side of the bead, 30 substantially as described, and for the purposes stated.

3. The combination, with a V-shaped metallic fence-post having an approximately semi-cylindrical bead on the edge formed by the 35 meeting of the sides, an opening through said beaded edge, and an anchor-brace integral with the post on each side of said opening, of an anchor formed from a rectangular piece of metal having its ends bent in opposite directions and having an integral rearwardly-extending tongue to pass through the opening in the post, and a key or other suitable device to pass between the tongue and the rear side of the bead, 40 substantially as described, and for 45 the purposes stated.

In testimony whereof we affix our signatures in presence of two witnesses.

LEGRAND B. HARMON.
JASPER N. NUTT.
